UNITED STATES PATENT OFFICE

MILDRED A. SMITH, OF ALBANY, NEW YORK, ASSIGNOR TO BAT-LES-LITE CORPORATION, OF ALBANY, NEW YORK, A CORPORATION OF NEW YORK

DESIGN FOR A FLASH LIGHT

Application filed March 31, 1931. Serial No. 39,312. Term of patent 14 years.

To all whom it may concern:

Be it known that I, MILDRED A. SMITH, a citizen of the United States and a resident of Albany, in the county of Albany and State of New York, have invented a new, original, and ornamental Design for Flashlight, of which the following is a specification, reference being had to the accompanying drawings, forming part thereof, wherein—

Fig. 1 is a side view of a flashlight showing my new design;

Figs. 2 to 5 are sections taken respectively on lines 2—2, 3—3, 4—4 and 5—5 of Fig. 1.

I claim:

The ornamental design for a flashlight as shown.

MILDRED A. SMITH.
